UNITED STATES PATENT OFFICE

161,521

CHOCOLATE DUCK

Richard M. Palmer, Reading, Pa.

Application August 9, 1950, Serial No. 11,677

Term of patent 7 years

(Cl. D82—2)

To all whom it may concern:

Be it known that I, Richard M. Palmer, a citizen of the United States of America, residing at 800 Old Wyomissing Road, Reading, in the county of Berks and State of Pennsylvania, have invented a new, original, and ornamental Design for a Chocolate Duck, of which the following is a specification, reference being had to the accompanying drawings, forming part thereof.

Fig. 2 is a front elevational view thereof.

Fig. 3 is a side elevational view showing the other side of the chocolate duck and

Fig. 4 is a rear elevational view thereof.

I claim:

The ornamental design for a chocolate duck, as shown.

RICHARD M. PALMER.
